UNITED STATES PATENT OFFICE.

JAMES R. MAXWELL, OF CINCINNATI, OHIO, AND EZRA COPE, OF COVINGTON, KENTUCKY.

DESIGN FOR A STEAM-ENGINE CYLINDER AND FRAME.

Specification forming part of Design No. 5,324, dated October 24, 1871.

To all whom it may concern:

Be it known that we, JAMES R. MAXWELL, of Cincinnati, in the county of Hamilton and State of Ohio, and EZRA COPE, of Covington, in the county of Kenton and State of Kentucky, have invented or produced a new and original Design for a Steam-Engine Cylinder and Frame, of which the following is a specification:

The nature of our design is fully represented in the accompanying photographic illustration, to which reference is made.

A represents the body of a steam or pump-cylinder surmounted by the base of the steam-chest; B B', cross-head guides extending from the cylinder, and curved transversely to their length; C, a circular flange, forming the end of the cross-

head guides; D, a web extending from the steam-chest to the flange C; E, a flanged web extending in line with the cylinder and guides, curved in shapes and sweeps to form one foot or support under the flange C, and bifurcated to form two feet or supports at the opposite ends of the structure, with upward-diverging counter curves terminating in journal-bearings F F.

What we claim as our invention is—

The design for steam-engine cylinder and frame, substantially as shown and described.

JAMES R. MAXWELL.
EZRA COPE.
